United States Patent Office

Des. 191,738
Patented Nov. 7, 1961

191,738

FAUCET

Milo J. Padavic, 312 N. 27th St., Quincy, Ill.

Filed July 8, 1960, Ser. No. 61,275

Term of patent 7 years

(Cl. D91—3)

FIG. 1 is a perspective view from the right of the faucet showing my new design;

FIG. 2 is an enlarged side elevational view thereof; and

FIG. 3 is a top plan view thereof as shown in FIG. 2. The dominant features of my design reside in the portions shown in full lines.

I claim:

The ornamental design for a faucet, as shown and described.
